UNITED STATES PATENT OFFICE.

ARTHUR R. PATTERSON AND SAMUEL J. TOMLINSON, JR., OF FAIRLAND, INDIANA.

TELEPHONE RETURN-TIME SIGNAL.

Application filed August 10, 1923. Serial No. 656,715.

To all whom it may concern:

Be it known that we, ARTHUR R. PATTERSON and SAMUEL J. TOMLINSON, Jr., citizens of the United States, residing at Fairland, in the county of Shelby and State of Indiana, have invented a new and useful Telephone Return-Time Signal, of which the following is a specification.

It is the object of our invention to indicate the time when a person will return who is away from his home or office when called on the telephone.

In carrying out our invention, we provide indicating devices, preferably substantially duplicates, at the subscriber's sub-station and at the central office. These indicating devices are in the nature of milli-ammeters, but preferably have clock-faces for the more convenient indication of time. At the subscriber's sub-station there is a two-point switch which the subscriber throws to the signaling instrument when he is about to leave his home or office, a battery for supplying the signaling current, a push-button for closing a local circuit through a battery from a subscriber's indicating instrument, which local circuit has a resistance corresponding to that of the line circuit and a rheostat which can be adjusted to allow different currents to flow to get any desired indication on the subscriber's signaling device —such as 10 o'clock, by way of example. The subscribers' signaling device and the line has also an adjustable resistance which can be set to raise the resistance of the circuit through the line and signaling instrument to a predetermined value, so that this circuit will be the same for all subscribers' lines. At the central station, the signaling instrument is suitably connected, as to segments on the point of the plug, so that as the operator starts to put the plug in the jack she may temporarily complete a circuit through her signaling device. If the signaling device at the sub-station of the subscriber being called is set, she does complete such circuit, which is supplied from the battery at the subscriber's sub-station, and which causes the signaling device at the central station to give the same indication as that for which the signaling device at the subscriber's sub-station is set.

The accompanying drawing illustrates our invention: The single figure of the drawing is a diagram showing the necessary connec-

tions and elements of our invention, at the central station and at one subscriber's sub-station.

The two line wires 10 and 11 lead from the two contacts 12 and 13 of the corresponding jack at the central station to the telephone instrument 14 at the subscriber's sub-station. At the subscriber's sub-station the line wire 11 leads to a two-point switch 15, having two contact points 16 and 17. When the switch 15 engages the contact 16, it connects the line wire 11 to the telephone 14. When the switch 15 engages the contact 17, it connects the line wire 11 to the subscriber's signaling device. The other line wire 10 is permanently connected to both the telephone sub-station 14 and the signaling device.

The subscriber's signaling device has a suitable current-measuring device, in the nature of a milli-ammeter. This may take any desired form; but for simplicity of diagrammatic illustration this milli-ammeter is shown as having a solenoid 20 which acts on a core 21 to turn a hand or pointer 22 over a dial 23 against the opposition of a spring 24; and the dial 23 is shown as a clock-face dial, for the convenient indication of time signals. This particular type of current-measuring device is shown merely because it is the easiest to illustrate, in connection with the desired complete-circle dial.

At the subscriber's sub-station there is also a source of current, such as a battery 25, conveniently formed of several dry cells. This battery supplies the signaling current which goes out from this particular sub-station, to give the signal to the operator at central; and likewise supplies the current for a local setting circuit by which the resistance of the signaling circuit to the central operator may be adjusted to give the desired indication on her milli-ammeter. This setting circuit is of the same resistance as the signaling circuit through the line, and there is an adjusting rheostat 26 which is included as part both of this local circuit and of the signaling circuit through the line.

The connections for obtaining this may be considerably varied, and we have shown one simple set of connections merely by way of illustration. In this illustrative set of connections, one terminal of the battery 25 and one terminal of the rheostat 26 are connected by a wire 27; the other terminal of

the rheostat 26 and one terminal of the solenoid 20 are connected by a wire 28; the other terminal of the solenoid 20 is connected by a wire 29 to one terminal of an 5 adjustable resistance 30; the other terminal of the adjustable resistance 30 is connected by a wire 31 to one terminal of a push-button 32; the other terminal of the push-button 32 is connected by a wire 33 to the other 10 terminal of the battery 25; the wire 33 also connects that terminal of the battery 25 to the contact point 17 of the double-throw switch 15; the wire 29 is also connected by a wire 34 to one terminal of a second adjustable resistance 35; and the other terminal of this second adjustable resistance 35 is connected by a wire 36 to the line wire 10. When the push-button 32 is depressed, it 15 closes the local setting circuit, which is from the battery 25, through the wire 27, rheostat 26, wire 28, solenoid 20, wire 29, adjustable resistance 30, wire 31, push-button 32, and wire 33, back to the battery 25. With the push-button 32 un-depressed, and the two-point switch 15 on the contact point 17, there 20 is a potential signaling circuit from the battery 25 through the wire 27, rheostat 26, wire 28, solenoid 20, wire 29, wire 34, adjustable resistance 35, wire 36, line wire 10, the connections shortly to be described and located at the operator's central station back to the line wire 11, then through the switch 15, contact point 17, and wire 33 back to the 25 battery 25. The adjustable resistance 35 is provided to adjust the signaling circuit for the subscriber's line to a predetermined value, which value will be the same for all subscribers' lines, so that signals which come in to the central station will not be disturbed by varying resistances of the lines. For this 30 same purpose of preventing disturbance and getting proper signals, the adjustable resistance 30 is adjusted to make that part of the local circuit from the wire 29 through such adjustable resistance to the battery 25 equal to the aforesaid predetermined value; so that the resistance in this local circuit will be the same as that of the signaling circuit through the line. The adjustable resistance 30 may 35 be calibrated at the factory, to set it for this predetermined value; but the adjustable resistance 35 must be calibrated by the electrician who installs the particular instrument. As a result of this, adjustment of the rheostat 26 to any point equally adjusts the resistance of the line signaling circuit and the resistance of the local setting circuit. 40 At the central station there is also a current-measuring device, likewise in the nature of a milli-ammeter. This is preferably substantially identical with that at the subscriber's sub-station. This also is illustrated in the same diagrammatic way, being shown as having a solenoid 20' which acts on a

core 21' to turn a hand or pointer 22' over a dial 23'. The dial 23', like the dial 23, is shown as a clock-face dial, for the convenient indication of time signals. The milli-ammeter at the central station is arranged 45 to be connected across the line 10-11 temporarily at the beginning of the insertion of the calling plug 40 into the jack 12-13; to complete the signaling circuit from the sub-station of the subscriber being called if 50 the two-point switch 15 at such sub-station is set for signaling by being on the contact point 17. While this may be accomplished in various ways, we have illustrated the calling plug 14 as having not only the two main sections 41 and 42 which are connected to the two conductors 43 and 44 of the plug-cord, but as having also two other segments 45 and 46 at the point of the plug, for engaging the jack contacts 12 and 13 as the calling plug 40 is started into the jack. These additional segments 45 and 46 at the point of the calling plug are connected by wires 47 and 48 to the two terminals of the solenoid 20'. 55

In operation, the two-point switch 15 at the subscriber's sub-station is normally on the contact 16, to render his signaling device inoperative and to connect his telephone 14 for ordinary calling and talking in the usual manner. With this connection, when the operator plugs into this subscriber's jack 12-13, the temporary engagement of the plug point-segments 45 and 46 with the jack contacts 12 and 13 causes no current flow through the solenoid 20' of the operator's milli-ammeter, and she gets no movement of the pointer 22'; so that she pushes her plug straight through to cause the segments 41 and 42 to engage the jack contacts 12 and 13, and thus completes the regular telephone circuit. 100

On the other hand, when the subscriber leaves his office, with the expectation of being back at some definite time, he shifts his switch 15 from the contact 16 to the contact 17, to disconnect his telephone from the line and connect his signaling device to the line. Further, either before or after thus shifting the switch 15, he depresses the push-button 32, and adjusts his rheostat 26 to vary the resistance of his local setting circuit until the current-flow therein is just sufficient to produce the desired indication by the pointer 22 on the dial 23. In other words, while holding the push-button 32 depressed, he shifts the rheostat 26 in one direction or the other until he sees that the pointer 22 gives the indication wanted—say 10 o'clock. Leaving the rheostat 26 so set, he releases the push-button 32, and goes on his way. 110

When now the operator attempts to call this subscriber, and in pushing in her calling plug 40 connects the point-segments 45 115

and 46 to the jack contacts 12 and 13, she completes the line signal circuit above described. The current in this circuit comes from the battery 25 at the subscriber's sub-station and flows through the solenoids 20 and 20' of both the milli-ammeter at the subscriber's sub-station and the milli-ammeter at the central station. The total resistance in this circuit is the same as that which is in the subscriber's local circuit. Therefore, the current coming from the same battery, (which in the meantime has had no opportunity to change materially in voltage,) the solenoid 20' at the central station pulls down its core 21' to produce an indication by the pointer 22' corresponding to that which the subscriber had obtained on his milli-ammeter—which we assumed was 10 o'clock. The operator at central, on seeing this indication, does not complete her call, but pulls out her calling plug 20, and announces to the subscriber who is calling that the subscriber being called is out and will return at 10 o'clock.

25 When the subscriber returns who has set his sub-station for signaling, he throws the switch 15 back to the contact point 16, and is ready to receive calls in the usual manner.

30 We claim as our invention:

1. A telephone return-time signal, comprising a current-measuring device at the subscriber's sub-station, a current-measuring device at the telephone central station, means for connecting the latter current-measuring device to the line leading to the subscriber's sub-station, a source of current at the subscriber's sub-station, a switch for connecting the subscriber's line at will to his telephone instrument or to said source of current and current-measuring device in series, a switch for completing a local circuit from said battery through said current-measuring device at the subscriber's sub-station independently of the line, and a rheostat in the circuit of said battery and said current-measuring device at the subscriber's sub-station for varying similarly either circuit which may be completed therethrough.

50 2. The combination set forth in claim 1, with the addition that said means for connecting the current-measuring instrument at the central station to the line leading to the subscriber's sub-station comprises segments on the point of the operator's calling plug and arranged to preliminarily engage the contacts of the jack of that subscriber's line.

55 3. The combination set forth in claim 1,

with the addition that said current-measuring instruments have clock-faces.

4. The combination set forth in claim 1, with the addition that said local circuit contains a resistance which makes the resistance of said local circuit substantially equal to that of the circuit which may be completed through the line and the current-measuring instrument at the central station.

5. The combination set forth in claim 1, with the addition that said local circuit contains a resistance which makes the resistance of said local circuit substantially equal to that of the circuit which may be completed through the line and the current-measuring instrument at the central station, and with the further addition that said resistance in the local circuit is adjustable.

6. The combination set forth in claim 1, with the addition of a resistance in the connection between the subscriber's line and said current-measuring device at the subscriber's sub-station.

7. The combination set forth in claim 1, with the addition of a resistance in the connection between the subscriber's line and said current-measuring device at the subscriber's sub-station, and with the further addition that said resistance is adjustable.

8. The combination set forth in claim 1, with the addition of a resistance in the connection between the subscriber's line and said current-measuring device at the subscriber's sub-station, and with the further addition that said local circuit contains a resistance which makes the resistance of said local circuit substantially equal to that of the circuit which may be completed through the line and the current-measuring instrument at the central station.

9. The combination set forth in claim 1, with the addition of a resistance in the connection between the subscriber's line and said current-measuring device at the subscriber's sub-station, and with the further addition that said local circuit contains a resistance which makes the resistance of said local circuit substantially equal to that of the circuit which may be completed through the line and the current-measuring instrument at the central station, both said resistances being adjustable.

In witness whereof, we have hereunto set our hands at Fairland, Shelby Co., Indiana, this 8th day of Aug., A. D. one thousand nine hundred and twenty three.

ARTHUR R. PATTERSON.
SAMUEL J. TOMLINSON, JR.
